INVENTOR
JAMES B. NEWLON
AND
CHRISTIAN BACKINGER

BY
Pierre James
ATTORNEY

UNITED STATES PATENT OFFICE.

JAMES B. NEWLON AND CHRISTIAN BACKINGER, OF SEATTLE, WASHINGTON.

WRENCH.

1,351,583.

Specification of Letters Patent. Patented Aug. 31, 1920.

Application filed September 25, 1919. Serial No. 326,120.

To all whom it may concern:

Be it known that we, JAMES B. NEWLON and CHRISTIAN BACKINGER, citizens of the United States, residing at Seattle, in the 5 county of King and State of Washington, have invented certain new and useful Improvements in Wrenches, of which the following is a specification.

This invention relates to monkey-wrenches 10 or the like.

The object of our invention is to simplify and improve the construction of wrenches of this character to enable the same to be more readily adjustable and more durable 15 and efficient in operation.

With these and other objects in view the invention consists in the novel construction, adaptation and combination of parts as will be hereinafter described and claimed.

20 In the accompanying drawings, Figure 1 is a view partly in side elevation and partly in longitudinal section of a wrench embodying our invention, shown applied. Fig. 2 is a similar view with the movable jaw and 25 associated parts in disengaged positions.

Fig. 3 is a fragmentary plan view of the wrench stock member. Fig. 4 is a sectional view taken through 4—4 of Fig. 2. Fig. 5 is a side elevational view of the movable 30 jaw member shown detached.

Referring to said drawings, the numeral 10 designates the shank provided with the usual stationary jaw 11 at one end and having its other end socketed in a handle 12.

35 The shank 10 is provided with a series of rack teeth 13 on the side edge 14 from which the jaw 11 projects.

15 represents a block or movable jaw having openings 16 through which the shank 40 extends.

To the rear of the jaw proper, indicated by 17, the block 15 is chambered as at 18 between side walls 19.

The front end of the chamber 18 is of an 45 arcuate shape, the upper portion 20 being unserrated while the lower portion is provided with teeth 21 which are desirably spaced at less distances apart than those of shank rack.

50 22 represents thumb lever extending into the block chamber as shown and is fulcrumed by a pin 23 to the side walls 19.

The arm of the lever within the block chamber is bifurcated and located therein 55 is a spur-wheel 24 having peripheral teeth adapted to engage the teeth of both the

shank rack and those of the movable jaw. The wheel 24 is mounted on an axle 25 whose ends extend through slots 26 of the lever bifurcations 27 into slots 28 provided 60 in the side walls 19 of the block. More particularly, the slots 28 of the block are arranged parallel, or nearly so, with the axis of the shank, and the lever slots 26 are arranged in inclined relations to the block 65 slots so that when the inner end of the thumb lever is raised or lowered the slots thereof will serve as cam elements to cause the spur wheel to be moved into and out of engagement with the jaw teeth 21 as respectively represented in Figs. 1 and 2. It is to be noted that in such movements the block slots 28 act through the medium of axle 25 to maintain the teeth of the spur wheel in continuous mesh with the shank 70 75 rack.

Assuming the spur wheel 24 to be in the relative position in which it is illustrated in Fig. 2, the movable jaw may be moved freely upon the shank 10 toward or from the stationary jaw 11.

When the movable jaw has been brought into a selected position, as shown for example against a nut in Fig. 1, the operator pushes down against the outer end of thumb lever 22 causing the bifurcated inner end to be swung upwardly whereupon the slots 26 act as cams to urge the spur wheel 24 forwardly into engagement with the portions 20 and 21 of the arcuate forward end 90 of block chamber 18.

With the spur wheel thus engaged, such toothed portion 21 serves to prevent the rotation of the spur wheel thereby locking the block to the shank, the unserrated portion 95 20 serves as a bearing against the spur wheel and through which is imparted any thrust received from the movable jaw directly to the shank 10 and relieves the axle 25 and block walls 19 of strains.

The invention will, it is thought be understood from the foregoing description of the preferred embodiment of our invention. It is apparent though that the invention is not necessarily limited thereto, as various 105 changes in the shape, proportions and arrangement of the parts may be made without departing from the principle of the invention and within the scope of the appended claims.

What we claim, is—

1. In a wrench, a stock comprising a sta-

100

105

110

tionary jaw and a shank extending therefrom, said shank being provided with rack teeth, a movable jaw slideable upon said shank, said movable jaw being chambered, 5 the front wall thereof being of an arcuate shape and provided with teeth, the side walls of the jaw chamber having slots arranged to be parallel with said shank, a bifurcated lever extending into the jaw chamber and provided with slots inclined with respect to said shank, a spur wheel positioned in the jaw chamber between the lever bifurcations, and an axle for said spur wheel, said axle engaging in both the lever 10 and jaw slots.

2. In a wrench, the combination of a stationary jaw, a shank therefor having teeth on one side of the same, a chambered block

slidably fitted at both of its ends to said shank and serving as a movable jaw, said block being provided interiorly with teeth, a spur wheel carried by said block and in continuous mesh with the shank teeth, and a means for adjustably moving said wheel parallel with said shank to effect the engagement or disengagement selectively of the wheel teeth with or from the block teeth.

Signed at Seattle, Washington, this 18th day of September, 1919.

JAMES B. NEWLON,
CHRISTIAN BACKINGER.
